Application August 13, 1942, Serial No. 454,710

13 Claims. (Cl. 332—25)

1

My invention relates to systems for the transmission of ultra high frequency electromagnetic waves and to devices for controlling the energy transmitted through dielectric wave guides.

It is now somewhat generally appreciated that high frequency electromagnetic waves may be transmitted through dielectric guides when the frequency at which the guide is excited is greater than a critical minimum or cut-off frequency. The energy is transmitted through the dielectric of the medium within the guide.

The types of waves which may be transmitted dielectrically through guides of this nature are manifold and have heretofore been classified generally into the E and H types. In the E type waves, the electromagnetic waves have both longitudinal and transverse components of electric field but only a transverse component of magnetic field. By use of the word transverse is meant transverse to the direction of wave propagation through the guide. In the H type waves, the electromagnetic waves have both longitudinal and transverse components of magnetic field but only a transverse component of electric field. The waves which may be transmitted through guides of this nature have been identified by the use of the subscripts as indicated, $E_{n,m}$ and $H_{n,m}$. The subscript n indicates the order and the subscript m indicates the mode of propagation. The order of the wave is determined by the manner in which the field intensity varies circumferentially around the axis of the guide, whereas the mode is determined by the manner of its variation with distance from the axis of the guide. Although hereinafter in the discussion of my invention an H_{01} type of wave is referred to, it is to be appreciated that my invention is applicable with equal facility to other H type waves as well as to E type waves.

It is an object of my invention to provide new and improved high frequency electromagnetic wave transmission systems.

It is another object of my invention to provide new and improved systems for controlling the transmission of electromagnetic waves dielectrically.

It is another object of my invention to provide new and improved devices for controlling the energy transmitted through dielectric wave guides.

It is a further object of my invention to provide in new and improved dielectric wave guide systems electric discharge devices for controlling the energy transmitted through the guide.

It is another object of my invention to provide

2

new and improved converting systems for dielectric wave guide apparatus.

It is a still further object of my invention to provide new and improved methods of controlling the propagation of electromagnetic waves through dielectric guides.

It is a still further object of my invention to provide new and improved methods of controlling the attenuating and transmitting characteristics of dielectric wave guides.

It is a still further object of my invention to provide new and improved means for amplitude, phase or frequency modulating electromagnetic waves transmitted through a dielectric wave guide.

Briefly stated, in accordance with the illustrated embodiments of my invention, I provide new and improved methods and apparatus for controlling electromagnetic waves which are propagated through hollow-pipe type wave guides. Generally speaking, I provide in a hollow-pipe type wave guide a region containing charged electric particles which controls the energy transmitted by the electromagnetic waves through the guide. Stated in other words, the presence of the region of charged electric particles, such as an electron beam, serves to control at will the effective dielectric constant of the medium within the guide through which the electromagnetic waves are transmitted.

By controlling the effective dielectric constant of the medium, the electromagnetic waves may not only be modulated in amplitude but may also be modulated in phase which makes it possible to control the phase relation of the electromagnetic waves received at output electrode means relative to the input or exciting electrode means. Furthermore, by the proper dimensioning of the guide, that is by the choice of the longitudinal spacing of the input and output electrode means, for a particular exciting frequency and characteristics of the guide, the density of the region of charged electric particles may be employed to modulate the frequency of the electromagnetic waves received at the output electrode means for a given electromagnetic excitation of the guide.

It will be appreciated, in view of the discussion appearing hereinafter, that the principles of my invention may be incorporated in amplitude modulation systems for electromagnetic waves and may also be applied to converting systems generally, such as phase and frequency modulating systems and converter or mixing circuits.

For a better understanding of my invention,

reference may be had to the following description taken in connection with the accompanying drawing, and its scope will be pointed out in the appended claims. Fig. 1 diagrammatically illustrates certain operating characteristics of dielectric guides of the hollow-pipe type. Figs. 2, 3 and 4 diagrammatically illustrate an embodiment of my invention wherein the region of charged electric particles constitutes an electron beam which is produced within a sealed structure associated with the guide. Fig. 5 diagrammatically illustrates another embodiment of my invention wherein the guide constitutes a sealed member or chamber and through which an electron beam is propagated longitudinally or along the axis of the guide. Fig. 6 diagrammatically illustrates an embodiment of my invention as applied to a transmitting and receiving system wherein a device built in accordance with the principles of my invention serves as a means for selectively connecting and disconnecting a receiving unit in a signalling system. Fig. 7 illustrates an embodiment of my invention as applied to a wave converting system such as an amplifier, phase or frequency converter. Fig. 8 diagrammatically illustrates an embodiment of my invention illustrated in Fig. 5 as applied to a modulating system for an amplitude, a phase, or a frequency modulating system where the modulation of the output waves is effected in response to a controlling signal. Fig. 9 diagrammatically illustrates a modification of the embodiment of my invention shown in Fig. 2 wherein the density of the electron beam may be controlled by a suitable grid structure.

As stated above, there is a critical minimum frequency or cut-off frequency for each dielectric guide, the value of which is determined by the dielectric constant of the medium within the guide through which the electromagnetic waves are propagated and the transverse dimensions of the guide. Below this value of critical frequency, the electromagnetic waves are rapidly attenuated and the energy thereof is not transmitted an appreciable distance along the axis of the guide. Above the critical frequency, the electromagnetic waves are propagated with an attenuation and velocity determined by the propagation constant of the guide. This propagation constant h may be expressed as follows:

$$h = \alpha + i\beta \quad (1)$$

where α is the attenuation constant and β is the phase constant and both are real quantities whose magnitudes depend upon frequency.

If the frequency is great enough, α is very small compared to β and waves are propagated without appreciable attenuation at a phase velocity

$$\frac{\omega}{\beta}$$

which varies with the transverse dimensions of the guide. When the excitation frequency is below the critical frequency, the Expression 1 may still be used but now α and β both become imaginary with the result that β determines the attenuation and α determines the extent of wave action. Since below the critical frequency β is again much larger than α , the attenuation is very pronounced and the wave action is very small. Physically, this means that transmission of waves through the guide is virtually nonexistent at frequencies below the cut-off frequency.

Although my invention may be applied with

equal facility to dielectric wave guides of various configuration, in the following discussion in order to present some fundamental considerations relative to the description of my invention, the fundamental aspects will be described with particular reference to dielectric wave guides having a rectangular cross section and wherein the height of the guide is a and the base is b .

The phase constant β may be expressed:

$$\beta = \left[\omega^2 \mu_1 \epsilon_1 - \left(\frac{n\pi}{a} \right)^2 - \left(\frac{m\pi}{b} \right)^2 \right]^{\frac{1}{2}} \quad (2)$$

where ω is the angular velocity of the wave propagated through the medium ($\omega = 2\pi f$ where f is the frequency of the wave), μ_1 is the permeability of the medium and ϵ_1 is the dielectric constant of the medium. The quantities n and m are, of course, the order and mode of the particular wave being transmitted through the guide.

The critical frequency f_0 may be defined as follows:

$$f_0 = \frac{1}{2\sqrt{\mu_1 \epsilon_1}} \left[\left(\frac{n}{a} \right)^2 + \left(\frac{m}{b} \right)^2 \right]^{\frac{1}{2}} \quad (3)$$

The wave length of the electromagnetic waves propagated through the guide may be defined as:

$$\lambda_c = \frac{2\pi}{\beta} \quad (4)$$

The phase velocity v_p of the wave transmitted through the guide is defined as follows:

$$v_p = \frac{\omega}{\beta} \quad (5)$$

An inspection of the above equations, particularly Equation 3 indicates that the critical frequency is smallest for the lowest order wave and increases as either n or m is increased, that is as the order of the wave becomes larger. Furthermore, it will be noted that as either dimension a or b of the wave guide is decreased, the critical frequency increases. In addition, it should be noted that the critical frequency may also be decreased by increasing the value of the dielectric constant or by employing a material having a larger dielectric constant.

In order to simplify still further the presentation of the subject matter of my invention, it will be assumed that the dielectric is air and the system is arranged for the transmission of an H_{01} type wave where the electric component of the field is perpendicular to b , in which case the phase constant and critical frequency expressed by Equations 2 and 3 become:

$$\beta = \left[\left(\frac{\omega}{c} \right)^2 - \left(\frac{\pi}{b} \right)^2 \right]^{\frac{1}{2}} \quad (6)$$

$$f_0 = \frac{c}{2b} \quad (7)$$

where c is the velocity of light in air.

The electromagnetic waves are propagated through the guide; that is, the expression for the progressive wave may be expressed as a function of the propagation constant and time. The electric intensity and the magnetic field may be expressed as follows:

$$E = (\text{real}) E_0 e^{-i\beta x + i\omega t} \quad (8)$$

$$H = (\text{real}) H_0 e^{-i\beta x + i\omega t} \quad (9)$$

An inspection of Equations 8 and 9 indicates that for given values of x , which is the distance along the axis of the guide for excitation above the critical frequency, the magnitude of the wave varies sinusoidally with time; and furthermore,

at a given instant the wave has a sinusoidal distribution along the axis.

Referring now to Fig. 1, the curve v_p represents the phase velocity, that is the speed at which a long sinusoidal wave train travels through the medium of the dielectric guide. The shaded portion of the curve shown in Fig. 1 represents the region of substantially complete attenuation; that is, the guide is opaque. At the critical frequency f_0 , the phase velocity theoretically is infinite and approaches the velocity of light as the applied frequency approaches infinity. The dotted portion of the curve v_p , representing the phase velocity, indicates the actual manner in which the phase velocity varies within the region around the critical frequency f_0 . The tapering off of the curve is due to the losses of the system, particularly the losses in the metallic conductor constituting the hollow pipe member. The phase velocity is to be distinguished from the phenomena associated with the rate of transmission of energy through the dielectric by electromagnetic waves. If an input signal is introduced into a dielectric guide, of course the output signal will be delayed in phase in accordance with the time of transit of the wave through the guide.

Reference may be had to Fig. 2 of the accompanying drawings wherein I provide, in accordance with my invention, new and improved methods and apparatus for controlling the propagation of electromagnetic waves through a dielectric guide which may be of rectangular cross section. The guide may include a hollow-pipe type member having walls of highly conductive material such as copper or brass. The guide may be fabricated and includes a base member 1, a top plate member 2 and an end member 3. The dielectric medium within the guide through which the electromagnetic waves are propagated may be any suitable dielectric, such as a gas, air, or an evacuated space.

The guide may be excited, that is the electromagnetic waves may be established within the guide by input electrode means such as a concentric or coaxial transmission line including a cylinder or tubular member 4 and a conductor 5, the latter of which may be attached to the top member 2. It will be understood that other forms of excitation may be employed, such as probes of various configurations, and that my invention is not limited to the particular arrangement for excitation shown. Furthermore, it will be appreciated that the configuration of the excitation means determines, in many instances, the type of electromagnetic waves which are established within the guide. The type illustrated serves to establish an H_{01} type wave.

A suitable radiating means, such as a flared horn 6, may be employed at the transmitting end of the guide where it is desired to transmit the waves into free space or into some other channel. Instead of using the horn at the end of the guide, an end wall may be employed and suitable probe or other output electrode means may be used to extract the energy from the waves.

I provide methods and apparatus for controlling the effective dielectric constant of the medium within the guide, thereby controlling the attenuating and transmitting characteristics thereof. More particularly, I provide a region of charged electric particles, such as electrons, which coact with the electromagnetic waves in the guide to control the energy transmitted thereby, or to control amplitude, phase or fre-

quency characteristics of the waves. This region may be coextensive with one dimension of the guide, such as a transverse dimension or the axial or longitudinal dimension, or the region may be localized within a portion of such dimension. One way in which my invention may be carried out is by providing an electron beam the path of which is transverse to the direction of propagation of the wave through the guide.

In Fig. 2 I have diagrammatically illustrated an arrangement wherein an electron beam is transmitted through the guide in a direction transverse to the direction of wave propagation. The means for producing the electron beam may be located in a sealed tubular housing or structure 7 which comprises partitions such as disks 8 and 9 positioned relative to the conducting surfaces or plate members 1 and 2 of the wave guide to afford a substantially continuous conducting path, thereby producing substantially no discontinuity in the conducting characteristics of the guide. This effect may be accomplished by providing plate members 1 and 2 with semicircular grooves or recesses into which the disks 8 and 9 may be inserted, thereby providing bayonet structures 10 and 11 suited for ready assembly.

Disks 8 and 9 are provided with openings 12 and 13, preferably rectangular, the major dimension of which is substantially equal to the base dimension b of the guide. The electron beam passes through the interior of the guide through openings 12 and 13. I may employ mesh grid structures 14 and 15 which may be welded or soldered to the disks 8 and 9.

The grids 14 and 15 serve several functions, one of which is to permit the passage of the electron beam therethrough and another of which is the provision of conducting paths across the openings 12 and 13. It will be noted that, as illustrated in Figs. 3 and 4 to be discussed presently, the grid structures 14 and 15 may constitute systems of conductors or wires which are orthogonal, that is mutually perpendicular. By virtue of the arrangement of the wires, conducting paths are provided for the flow of transverse and longitudinal current incident to the passage of the electromagnetic waves through the guide.

It will be appreciated that the disks 8 and 9 afford a central region or chamber which lies within the interior of the wave guide. Suitable insulating tubular members 16, 17 and 18 position the disks 8 and 9 and also afford spaces within which a cathode 19 and an anode 20 may be placed to produce the electron beam. Cathode 19 may be of the indirectly heated type comprising a heating element or filament 21, the energizing conductors for which extend through a suitable press or glass seal 22 which is supported by a tubular conductor 23 which serves as a connection to the cathode 21. The press or seal 22 may be connected to the conductor 23 by means of a flanged metallic tubing 24.

The electron beam density may, of course, be controlled by varying the voltage applied between the anode 20 and the cathode 19. It will be appreciated that the electron beam density may be varied in response to any predetermined controlling signal, thereby controlling the effective dielectric constant of the medium within the guide at will. Diagrammatically, for the purposes of illustrating one way in which the electron beam density may be varied, I have shown a battery B and an adjusting means for controlling the potential difference between anode and cathode,

A switch C, of course, may be connected in this circuit.

Fig. 3 shows in perspective the portion of the structure 7 including the disks 8 and 9 and an insulating cylinder 17 which positions the disks. Grids 14 and 15 are also shown to cover the rectangular openings 12 and 13.

In Fig. 4 a perspective view is illustrated of apparatus built in accordance with one embodiment of my invention, such as Fig. 2, and shows the manner in which the anode 19 and the cathode 20 are positioned relative to the rectangular openings.

In explaining one method of operating the embodiment of my invention illustrated in Fig. 2, it will be assumed that the guide is excited at a frequency slightly above the critical frequency of the guide under those conditions where the electron beam density is zero. In this case, the electromagnetic waves will be propagated through the guide and the phase constant, the velocity of propagation, and the wave length of the transmitted wave will, of course, be determined by the equations discussed hereinbefore. Upon the transmission of the electron beam between the anode 20 and the cathode 19, the dielectric constant of the medium within the guide, which for the purposes of explanation will be assumed as being air, will be decreased to a value less than 1, consequently resulting in an effective dielectric constant which is less than unity and thereby raising the "effective" critical frequency of the guide. As a result, the electromagnetic waves will be highly attenuated and energy will be transmitted only a very small distance along the guide from the input electrode means. Upon interruption of the electron beam, the effective dielectric constant becomes equal to that of air and the waves are propagated through the guide. Therefore, one application of my invention may be represented as rapidly changing a dielectric wave guide system from an attenuator to a wave passer or propagator.

It is to be understood that in accordance with the teachings of my invention, the wave guide system may be designed so that transition from an attenuator or a propagator, or vice versa, may be accomplished by changing the density of the electron beam from one of higher intensity to one of lower intensity, or vice versa, and that it is not necessary for the utilization of my invention to interrupt completely the electron beam.

The manner in which the electron beam affects the dielectric constant of the medium through which the waves are propagated may be viewed from the standpoint of the interaction of the transmitted waves and the waves produced by the electron beam. For a more theoretical explanation of the manner in which the transmitted waves and the waves of the electron beam interact to modify the effective dielectric component of the medium, reference may be had to my paper entitled "Space charge and field waves in an electron beam," published in the August 1, 1939, issue, vol. 56, of *Physical Review*.

Generally speaking, it may be said that the effective dielectric constant of the medium is a function of the difference of the dielectric constant of the medium with no electron beam present and a quantity which is directly proportional to the number of charged particles per unit volume, the square of the unit charge of each particle, and inversely proportional to the mass of each charge and some function of the frequency,

and if a magnetic field is present, some function of the magnetic field.

It will, therefore, be appreciated that as the charge density of the electron beam increases, the effective dielectric constant decreases, being at all times less than 1 due to the presence of the beam.

Referring again to Fig. 1, it will therefore be appreciated that by control of the density of the electron beam the operation of the wave guide system shown in Figs. 2 and 4 may be selectively controlled to effect transitions from the attenuation region to the transmitting region. As the intensity of the electron beam is increased, the effective dielectric decreases to a value which prevents the propagation of waves through the guide. That is, for increased values of an electron beam intensity, the phase velocity v_p becomes greater, at all times being greater than the velocity of light, and approaches infinity at the cut-off frequency; the cut-off frequency, of course, being a function of the effective dielectric constant. Moving in the other direction along curve v_p , it will be appreciated that as electron beam density is decreased, the effective dielectric constant of the medium is increased to that value which will permit propagation of electromagnetic waves for the particular value of frequency and the dimensions of the guide.

The embodiments of my invention illustrated in Figs. 2 and 4 may be operated as an amplitude modulator, that is may be operated to control the magnitude of the electromagnetic waves transmitted by the guide. For example, the system may be made to operate along a vertical portion $q-r$ of the attenuation curve α shown in Fig. 1. By controlling the electron beam intensity, the attenuation within this region is materially varied, causing an appreciable variation in the amplitude of the transmitted waves. Consequently, the waves transmitted through the guide, or the waves received at electrode receiving means, are controlled in magnitude in response to the beam density.

In Fig. 5 I have diagrammatically illustrated another embodiment of my invention as applied to a dielectric wave guide which may be employed as a phase modulator or a frequency modulator. In the arrangement of Fig. 5, the wave guide may also be of rectangular cross section of dimensions similar to that shown in Figs. 2 and 4 and in which the entire guide through which waves are propagated is hermetically sealed so that the electron beam may be transmitted longitudinally through the evacuated guide, the end wall or plate 25 serving as an anode and the end wall or plate 26 being provided with a rectangular opening including a grid 27 through which the electron beam passes. A cathode 28 of the indirectly heated type may be employed, positioned as illustrated relative to the guide and the grid 27, as a source of electrons. Cathode heating current is supplied to the filament 29 through conductors 30 and 31 and a conductor 32 is connected to the cathode and serves as a cathode lead. Conductors 33-32 may be supported by a glass press 33 and terminate in a plug of the type indicated as a ready means for establishing a cathode heating circuit and cathode connection.

A tapered metallic end enclosure 34 which is sealed may be employed to connect the metallic walls of the guide to the glass press assembly 33. This member may be sealed to the walls of the press by a suitable glass to metal seal, such as nickel, iron and cobalt alloy. I provide input

electrode means which may take the form of a concentric or coaxial transmission line comprising a tubular member 35 and a coaxial conductor 36, the former being connected to the top of the wave guide and the latter being conductively connected to the bottom of the guide. A seal 37 may be positioned as indicated to maintain an evacuated space within the guide.

Inasmuch as the electromagnetic waves are transmitted longitudinally through the guide at a definite frequency and have a wave length λ_g as indicated above, where it is desired to phase modulate the waves relative to input signals, I provide output electrode means which may comprise a concentric or coaxial transmission line including a tubular conductor 38 and a conductor 39, the former of which may be connected to the top of the guide and the latter of which is conductively connected to the bottom. Of course, suitable sealing means is also provided for this line. The distance L between the centers of the input and output electrode means determines (in conjunction with the wave length of the transmitted wave, the transverse dimensions of the guide and the electron beam density) the angle of displacement or lag between the input signal and the output signals.

Consequently, it is to be understood that I provide means whereby an electromagnetic wave may be phase modulated with respect to the input or excitation wave by controlling the electron beam density. In general terms, the beam density controls the phase constant and consequently, controls the phase velocity and wave length of the transmitted wave. By varying the density of the beam, the angle of displacement between input and output electrode means is accordingly controllable.

One way in which the embodiment of my invention illustrated in Fig. 5 may be operated is to design the system, that is the transverse dimensions of the guide, the length L , and the exciting frequency for a given value of electron beam density so that for a particular condition of operation the phase displacement between the input and output waves is zero. By decreasing the density of the electron beam, the effective dielectric constant is consequently increased and the wave length λ_g of the transmitted wave is consequently decreased, producing a phase displacement which is a function of the beam density. For example, when the electron beam density is maximum, the system may be arranged so that the phase displacement is practically zero, and for zero beam density the phase displacement may be close to

$$\frac{L}{\lambda_g} \times 2\pi \text{ radians}$$

When the devices built in accordance with my invention, such as that shown in Fig. 5, are employed as phase or frequency modulators, the system may be operated within that region $g-h$ of the attenuation curve shown in Fig. 1 where the amplitude of the transmitted waves is not appreciably affected as the phase constant B or the phase velocity v_p of the transmitted waves varies.

Of course, the arrangement shown in Fig. 5 may also be operated as an amplitude modulator, in which case the system for the most effective results should be operated along a vertical portion of the attenuation curve α of Fig. 1.

A wave guide system constructed in accordance with my invention, therefore, uses charged particles, such as electrons, in the medium to con-

trol the transit time of the wave through the guide since a variation in the electrode beam parameters is a means of changing the phase or time delay between the input and output electrode means. To obtain appreciable phase modulation in this manner, it is appreciated that the field of application is to extremely high frequency waves. However, systems built in accordance with my invention may be applied to arrangements where it is desired to obtain frequency modulation of an electromagnetic wave. For example, the distance L may be made 1 meter long. If the electron beam density is made to vary between two extreme values which correspond to a large phase velocity compared with that of light and approximate light velocity, then something of the order of $100 \times 2\pi$ radians phase shift may be obtained for a 1 centimeter wave. Such frequency modulation is sufficient for a wide band frequency modulation communication system.

When it is desired to focus the electron beam, I may employ suitable apparatus such as a focusing magnetic coil 40 having its principal axis preferably in coincidence with the longitudinal axis of the guide. The resultant characteristics of an electron beam and an electromagnetic wave when the beam is focused in this manner is treated to some extent in my above identified paper.

Fig. 6 diagrammatically illustrates an embodiment of my invention as applied to a receiving-transmitting system wherein a high frequency transmitter 41 is connected to a radiative and 35 reception element, such as an antenna 42, and wherein a receiver 43 is employed. In some direction systems, such as those used for the location of distant objects, it is desired to prevent reception by the receiver of the high intensity 40 electromagnetic waves emanating from a nearby transmitter due to the fact that the intensity of the transmitted waves is sufficiently great in some instances to damage the receiver. I connect between the transmitter and the receiver 45 one of the devices built in accordance with my invention, such as the arrangements shown in Fig. 2 and Fig. 5, so that the receiver is protected while the transmitter is operating. The device when used as a protective or control element is shown diagrammatically as 44 in Fig. 6. When device 44 is employed in this manner, it is to be understood that in place of the flared horn of Fig. 2 the receiver may be connected by means of an output electrode means such as that shown in Fig. 5.

I also provide means for selectively controlling the operation of the device 44 and the transmitter 41. Referring to Fig. 6, I have there shown diagrammatically a simple arrangement 60 comprising a key 45 provided with contacts 46 and 47, the former of which are closed to establish an electron beam in the device 44, thereby protecting the receiver when the transmitter is in operation. The contacts 47 are connected to 65 render the transmitter operative by depression of the key. The key 45 may be arranged so that contacts 46 and 47 are closed simultaneously, or contacts 46 are closed before contacts 47, so that the electron beam is always present within the device 44 at the time the transmitter is initiated in its operation.

It is within the purview of my invention to control the device 44 by other means such as electronic means wherein the electron beam is established and interrupted in response to the

intensity of the outgoing electromagnetic waves and the received electromagnetic waves. For example, I may employ a protective device which establishes the electron beam when the intensity of the electromagnetic waves of the system or antenna is above a predetermined value as, for example, when the transmitter is operating, thereby protecting the receiver.

When the transmitter is operating, the electron beam is established within the device 44 causing it to operate as an attenuator. When it is desired to receive the reflected waves caused by distant objects, the transmitter of course is not operated and the device 44 permits the reception of signals by the receiver 43. This is, of course, effected by decreasing the electron beam density or interrupting the beam completely so that the device 44 operates as a propagator of electromagnetic waves.

In Fig. 7 there is diagrammatically illustrated another application of my invention and which includes a device generally similar to that shown in Figs. 2 and 4 but modified by the employment of output electrode means, such as a concentric or coaxial transmission line including a tubular member 48 and a conductor 49. Other elements of the device have been assigned reference numerals corresponding to those of Fig. 2. In this arrangement of my invention, the input electrode means may be connected to an ultra high frequency generator or an antenna, and the output electrode means may be connected to a receiving device. The control of the electron beam may be effected in response to a signal, produced by a device 50, which is amplified by a suitable electronic amplifier 51. It is to be understood that the control means for the electron means may be connected directly to the input electrode means comprising the tubular member 4 and the conductor 5, in which case for an arrangement similar to Fig. 6 the electron beam will be established if the intensity of the electromagnetic waves in the antenna 42 circuit exceeds a predetermined value.

The arrangement shown in Fig. 7 may also be operated as an amplifier for the signals produced by the device 50, in which case the magnitude of the waves received at the output electrode means may be controlled by the intensity of the electron beam.

Fig. 8 is another diagrammatic illustration of one way in which the device shown in Fig. 5 may be applied to a modulating system, such as a magnitude, phase or frequency modulation system. In this arrangement, the voltage impressed across the anode and cathode, which produces the electron beam, is varied in response to a signal source or in response to a received signal by means of a device 52. If required or desired, an electronic amplifier 53 may be interposed between the signal source and the wave guide.

In the embodiments of my invention described heretofore, the electron beam density has been controlled by variation of the anode-cathode voltage. In Fig. 9 I have diagrammatically illustrated a modification of the arrangement shown in Fig. 2 wherein the electron beam density may be controlled by means of a grid structure, such as a grid 54, which may be positioned intermediate the cathode 19 and the grid mesh 14. The grid 15 may be insulated from the plates 1 and 2 of the wave guide by means of a ring of insulation 55 so that the

potential of grid 54 may be maintained negative relative to that of the cathode 19. Grid 54 may be supported and attached to a metallic disk 56 positioned between the insulating tubes 16 and 17, and may be connected to an external circuit through a suitable high frequency structure or transmission line if it is desired to vary the potential thereof at high frequency.

It will be apparent that the various circuit arrangements for controlling the intensity of the beam and for effecting control of the transmitted waves in the manner explained heretofore may also be applied with equal facility to the arrangement of Fig. 9 wherein the potential of grid 54 serves to effect the desired control.

The electrostatic control member or grid 54 may also be positioned between grids 14 and 15, that is may be positioned to lie within the portion of the electron beam within the wave guide.

In a similar manner, it will also be appreciated that the embodiment of my invention shown in Fig. 5 may also be provided with an additional grid structure for controlling the intensity of the electron beam. Such a grid structure may be placed between the cathode 28 and the grid 27, or may be positioned within the guide at any optimum point along the beam.

While I have shown and described my invention as applied to particular systems embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, a dielectric wave guide comprising an elongated hollow member, cathode means external to said member for producing within the space enclosed by said hollow member an electron stream having a component parallel to the longitudinal axis of said member and occupying substantially the entire wave guiding region therein, means coupled to said member for exciting said member at a frequency somewhat greater than the cut-off frequency established by the dimensions of said member and the dielectric constant of the medium within said member, output means spaced longitudinally from said last mentioned means by a distance which is relatively great with respect to the wave length corresponding to the frequency of excitation of said member, and means for controlling the charge density of said stream to phase modulate the electromagnetic waves received at said output means.

2. In combination, a dielectric wave guide comprising an elongated evacuated hollow member for transmitting electromagnetic waves dielectrically and comprising at one end thereof a cathode and at the other end thereof an anode for producing an electron beam along the longitudinal axis of said guide, means connected to said guide for establishing electromagnetic waves therein, and output electrode means spaced longitudinally from said last mentioned means.

3. In combination, an elongated evacuated dielectric wave guide having at one end thereof a metallic wall which serves as an anode and at the other end thereof a wall provided with an opening, a grid lying across said opening to provide a path for the flow of current incident to the waves in said guide, an evacuated member

positioned to enclose the end of said guide providing said opening and having therein a cathode, the electrons emitted thereby passing through the grid to the end plate constituting said anode, input electrode means for establishing electromagnetic waves within said guide, and output electrode means spaced longitudinally from said input electrode means.

4. In combination, a dielectric wave guide comprising an elongated hollow member, means for producing an electron beam within the space enclosed by said hollow member, means coupled to said member for exciting said member at a frequency somewhat greater than the cut-off frequency established by the dimensions of said member and the dielectric constant of the medium within said member, electromagnetic means for focusing said beam along a path substantially coextensive with the region of effective wave propagation within said member, output means spaced longitudinally from said exciting means by a distance which is relatively great with respect to the wave length corresponding to the said frequency of excitation of said member, and means for controlling the charge density of said beam to phase modulate the electromagnetic waves received at said output means.

5. In combination, a dielectric wave guide of the hollow-pipe type comprising an evacuated structure including means for producing an electron beam along the longitudinal axis of said guide, means for establishing in said guide electromagnetic waves of high frequency, output electrode means displaced longitudinally of said guide from said last means, and means for controlling the intensity of said beam to control the energy of said waves at the output electrode means.

6. In combination, a dielectric wave guide of the hollow-pipe type comprising a metallic member through which electromagnetic waves may be propagated, means for establishing electromagnetic waves in said member, an evacuated structure supported by said guide and extending therethrough in a direction perpendicular to the direction of propagation of the electromagnetic waves through said guide, electric discharge means within said structure for producing an electron beam, and means for controlling the intensity of said beam to control the amount of energy transmitted by said waves.

7. In combination, a dielectric wave guide for propagating electromagnetic waves and comprising a metallic member of rectangular cross section, a cylindrical structure extending through said member transverse to the direction of propagation of said waves and comprising a non-resonant central portion bounded by a pair of perforate coaxial metallic disks positioned contiguous to the top and the bottom of said guide to afford a substantially continuous conducting surface, and means within said structure and displaced from the central portion for producing an electron beam.

8. In combination, a dielectric wave guide for propagating electromagnetic waves and comprising a metallic member of rectangular cross section, a cylindrical structure extending through said member transverse to the direction of propagation of said waves and comprising a central portion bounded by a pair of coaxial metallic disks contiguous to the top and bottom of said guide to afford a substantially continuous conducting surface, said disks being provided with rectangular openings the principal dimension of

which is substantially equal to a transverse dimension of said guide, a pair of conducting grids attached to said disks and substantially covering said openings to provide transverse and longitudinal paths for the conduction of current incident to the transmission of electromagnetic waves through said guide, means positioned within said structure comprising an anode and a cathode for producing an electron beam which passes through said openings, and an electrostatic grid control means for controlling the electron beam density.

9. In combination, a dielectric wave guide of the hollow-pipe type comprising a metallic member through which electromagnetic waves may be propagated, means for establishing electromagnetic waves within said guide, a tubular structure extending through said member substantially perpendicular to the direction of wave propagation through said guide and comprising a central chamber including metallic partitions positioned relative to said member to afford substantially continuous conductive paths, said partitions being provided with openings, grid members lying across said openings and attached to said partitions and serving as longitudinal and transverse conducting paths for the flow of electric current incident to the transmission of the electromagnetic waves through said guide, means within said structure for producing an electron beam, and second grid means for controlling the intensity of said beam.

10. In combination, a dielectric wave guide of the hollow-pipe type comprising a metallic member through which electromagnetic waves may be propagated, means for establishing electromagnetic waves within said guide, a tubular structure extending through said member substantially perpendicular to the direction of wave propagation through said guide and comprising a central chamber determined by metallic partitions positioned relative to said member to afford a substantially continuous conductive path, said partitions being provided with openings, grid members substantially covering said openings and attached to said partitions and each serving as longitudinal and transverse conducting paths for the flow of current incident to the transmission of the electromagnetic waves through said guide, and means within said structure for producing an electron beam.

11. In combination, a guide for transmitting electromagnetic waves dielectrically including a hollow-pipe type member, means for establishing electromagnetic waves in said member at a frequency close to but above cutoff, discharge-pervious means forming an electrically continuous part of the wall structure of said member, means for producing an electronic discharge extending through said discharge-pervious means and within said member in a region traversed by said waves and means for controlling said electronic discharge to vary the propagation of said waves.

12. In combination, a guide for transmitting electromagnetic waves dielectrically including a hollow-pipe member, means for propagating electromagnetic waves longitudinally within said member at a frequency close to but above cutoff, means for producing a stream of charged particles within said member in a direction parallel to the direction of wave propagation and in a region substantially coextensive with the propagating path, and means for producing controlled variations in the density of said waves from point to point along said propagating path thereby to

15

produce phase modulation of said electromagnetic waves.

13. In combination, a dielectric wave guide comprising an elongated hollow member, means for producing within the space enclosed by said member an electron stream parallel to the longitudinal axis of said member and extending along the wave-guiding portion thereof, means coupled to said member for producing wave propagation longitudinally therein at a frequency close to but above cutoff, output means within said member and spaced longitudinally from said last-named means by a distance which is relatively great with respect to the wave length of said electromagnetic waves, and means for producing controlled variations in the density of said electron stream from point to point along its axis to phase modulate the electromagnetic waves received at said output means.
